PHASING NETWORK

Gustave Longo, St. Avit-Senieur, France

Application June 9, 1939, Serial No. 278,243
In France October 11, 1938

8 Claims. (Cl. 178—44)

The invention relates to a system or method for the radiation of modulated radio-electric waves and apparatus for carrying out the functions of the system.

5 An essential object of the invention is to render more economical the functioning of the transmitter; for this reason, it is particularly applicable to radio broadcasting stations.

It is known that the radiation of modulated 10 waves is particularly inefficient, above all if the percentage of modulation should be able to attain 100 percent, because of the great variations in the instantaneous power radiated as compared to the average power. This new system eliminates 15 these variations; the power radiated is at all times equal to the average power.

The invention will be described by referring to the accompanying drawing in which Figure 1 is a diagrammatic representation of an antenna array; Figure 2 is a schematic diagram of one embodiment of the invention; Figure 3 is a diagram of the phase splitting network used in the invention; and Figure 4 is a schematic diagram of another embodiment of the invention. Similar 20 reference numerals have been used to indicate similar elements.

In the system of the invention, the radiation is effected through five antennas, preferably vertical, one of which is a central antenna, corresponding to the usual antenna, and four are peripheral antennas, identical to each other, arranged at the corners of a square, the center of which is occupied by the first antenna. In Fig. 1, the circle A_0 represents the outline of the central antenna on the ground, the circles A_1 , A_2 , A_3 , A_4 the outlines of the peripheral antennas. The distance l of each of the peripheral antennas from the central antenna is preferably small compared to the wave length λ of the transmitter—for example, of the order of

$$\frac{\lambda}{12}$$

45 It is desirable, at least for the application of the system to radio broadcasting, that the field given by the series of four peripheral antennas present a distribution in height (the field diagram in the vertical plane) practically equal to the distribution in height of the field given by the central antenna. If this central antenna is constituted, as in many modern stations, by a mast antenna of great height, the said resultant may be easily obtained by giving to the peripheral antennas a suitable height, lower than that

of the mast; these peripheral antennas may be conveniently supported by the mast itself.

The central antenna A_0 (Fig. 2) is intended to emit the single carrier wave; it should thus be energized by a current of high frequency and constant amplitude. As, moreover, the field caused by the series of the four peripheral antennas has no action on the current in the central antenna, the excitation of this antenna demands a power at all times constant, and consequently the antenna may be excited by a thermionic tube (or a series of tubes) S_0 operating as class C amplifiers.

The two pairs of peripheral antennas aligned with the central antenna, that is to say, the antennas A_1 and A_3 of the one part, and the antennas A_2 and A_4 of the other part, are excited separately, the first pair by a tube (or a series of tubes) S' , and the other pair by a tube (or series of tubes) S'' , the tubes being identical to each other and identically coupled to the respective antennas. The two antennas coupled to the same tube are excited in a fashion entirely symmetrical, that is to say, in such manner that the current in one of the antennas is at the same time equal and opposite to the current in the other. The tubes S' and S'' preferably operate in class B and in linear fashion; the voltage for the excitation of their control grids may be obtained in the manner described below.

Let e be the voltage of the acoustic current which should modulate the wave emitted by the station, at any time whatsoever; this voltage may be represented by a sum of sinusoidal terms, and therefore, with the customary notations,

$$e = \sum e_n \sin (\Omega_n t - \phi_n)$$

By means of the arrangement above described, or by any other process, the voltage e must be transformed into the two voltages e' and e'' having the following expression:

$$e' = K \sum e_n \sin (\Omega_n t - B_n);$$

$$e'' = K \sum e_n \cos (\Omega_n t - B_n)$$

Where K is any constant.

Let

$$E = \sqrt{1/2 \sum e_n^2}$$

be the effective value of e , and E_0 the limit value that E should never go beyond during the operation of the transmitter.

Let ω be the pulsation of high frequency of the transmitter, through the voltage e' of the one part and the voltage e'' of the other part; the oscillation of pulsation ω is modulated sepa-

rately with the carrier suppressed in such manner as to obtain two voltages.

$$K_1 e' \sin \omega t \quad K_1 e'' \sin \omega t$$

5 where K_1 is a constant; these two voltages are submitted separately to the identical amplification; after amplification, the first voltage controls, in suitable fashion, the tube S' , and the other voltage controls, in identical fashion, the tube S'' . In this manner there is obtained in the antennas A_1 and A_3 a current of high frequency which, K_2 being a constant, may be represented by

$$\pm K_2 e' \sin \omega t$$

15 And in the antennas A_2 and A_4 a current

$$\pm K_2 e'' \sin \omega t$$

The effective average values of these currents are equal to each other and proportional to E ; 20 let

$$\frac{E}{E_0} I_1$$

25 be this effective average common value, I_1 being then always invariable during the operation of the station.

If I_0 be the effective invariable value of the current in the central antenna, this current should be in the form,

$$30 \quad \sqrt{2} I_0 \cos \omega t$$

that is to say, in quadrature with the current in the peripheral antennas.

The wave emitted by the series of five antennas is modulated according to the voltage of the 35 acoustic current; in order that the relation between the rate of modulation and the effective voltage E of the acoustic current may have the proper value, the value of the relation may be conveniently regulated, once for all times, as 40

$$\frac{I_1}{I_0}$$

45 Under these conditions, the wave emitted by the transmitter in any vertical plane which passes through the central antenna does not differ in any way from the wave which would be emitted by a station of the ordinary type; but the instantaneous value of the modulation of the emitted wave, contrary to that which arrives for ordinary 50 stations, varies from one vertical plane to the other according to the law that the instantaneous power of the radiation is always equal to the average power.

The system permits of employing a number of 55 peripheral antennas different from four, always symmetrically arranged with regard to the central antenna, the currents in the antennas being modulated according to the polyphase symmetrical systems, in a manner similar to the preceding one and easy to determine. In any case, the corresponding transformation of the acoustic 60 current of modulation may be obtained by the arrangement described above.

In the arrangement of antennas just described, 65 the carrier wave of the radiation is produced by the central antenna and the waves of the two side bands by the peripheral antennas. Other arrangements may also be realized; for example, the central antenna may be eliminated, the function 70 of which will be performed, in addition to their own function, by the peripheral antennas. In this case, the peripheral antennas should have the same position as before, and may be fed in the same manner with regard to their particular 75 current; but the tube S_0 (through connections

that will be perceived immediately), in place of feeding the central antenna, feeds the series of peripheral antennas in parallel; thus the current of constant amplitude which produces the carrier wave, uniformly distributed in the peripheral antennas, is added in each antenna to the particular current thereof.

5 The device of this system may find applications among radio beacons and analogous arrangements. If the current of modulation is 10 constituted by a single sinusoidal term of frequency f , the amplitude of the wave emitted presents a maximum in a vertical plane which turns around the central antenna at an angular constant speed $2\pi f$.

15 It will be seen that what is essential in the system is the form and spatial arrangement defined above (or equivalent form and arrangement) of the antenna currents; naturally, any manner of furnishing the currents to the antennas may be employed. What follows is the 20 description of the arrangement for effecting the transformation of the modulation current which, as has been seen above, is necessary to the functioning of the system.

25 The fundamental element of the arrangement is represented by a double row of elementary impedances, as, for example, the two rows P'_1 and P'_2 (Fig. 3); each elementary impedance is formed by a resistor r' , an inductor L'_1 and a capacitor C'_1 in series; a certain number of these elementary impedances r' , L'_1 , C'_1 , etc. (which may also be called simple circuits) arranged in parallel, compose one row P'_1 ; the two ranges P'_1 , P'_2 are arranged in series between two input terminals B_1 and B_2 . Between the two rows P'_1 , P'_2 , a resistor r is inserted; a terminal B' is connected to the midpoint of the resistor r which is an output terminal of the double row. Two or more of these double rows P'_1 , P'_2 , P''_1 , P''_2 suitably joined, constitute the essential part of the arrangement.

30 Each double row of simple circuits should present the following characteristics: Let N be the total number of simple circuits which compose 35 the double range. The resistors r' of each of these circuits have the same value in all the circuits; on the other hand, the value of the inductors L'_1 , etc., and that of the capacitors C'_1 , etc., vary from one circuit to another in the manner 40 explained below.

45 Going from the circuit, the inductor of which has the highest value, and successively in the order of decreasing inductances, each circuit is distinguished by an order number

$$1, 2, 3, \dots, N$$

50 The circuits having the odd order numbers compose the range P'_1 ; the others, the range P'_2 .

If L_9 be the value of the inductor and C_9 that of the capacitor of the generic circuit the order 60 number of which is 9; μ being a positive number conveniently chosen, it is necessary that, between the values L_9 and C_9 of the one part, and, of the other part, the values L_{10} and C_{10} of the inductor and capacitor of the successive circuit, 65 the following fundamental relation be satisfied, whatever may be 9 from 1 to $N-1$:

$$\frac{L_9}{L_{10}} = \frac{C_9}{C_{10}} = \mu$$

70 The result is that the relation

$$\frac{L_9}{C_9}$$

75 is an independent constant of 9.

Let f_m be the lowest frequency of the band of frequencies that the arrangement is intended to cover, and f_M the highest; this band is not necessarily a band of acoustic frequencies, but may be 5 of any kind whatever.

Let

$$f_0 = \frac{1}{2\pi\sqrt{L_0 C_0}}$$

10 be the frequency of resonance of the circuit 9; that is to say, the frequency for which the value of the impedance of the circuit is reduced to that of its resistance R . The values of these frequencies f_1 to f_n form, evidently, a geometric progression the reason of which is μ .

15 In general, the following two conditions should be satisfied:

(1) The relation

$$\frac{f_n}{f_1}$$

20 should be extremely great compared to the relation:

$$\frac{f_M}{f_m}$$

25 (2) On the contrary, the geometric averages $\sqrt{f_1 f_n}$ and $\sqrt{f_m f_M}$ should be, in a sense otherwise very large, of the same order of greatness.

The manner of realizing the arrangement may 30 be deducted from the following generic example:

Let two double ranges of simple circuits P'_1 and P'_2 of the one part, and P''_1 and P''_2 of the other part (Fig. 3) each be constituted in the manner just described; the values of N , μ , R , r' will be the 35 same for the two double ranges. Let L'_9 and C'_9 be the values of the inductor and the capacitor of the circuit 9 of the first double range, L''_9 and C''_9 the corresponding values for the circuit 9 of the other double range; s being any number lower 40 in absolute value than unity, the second fundamental relation following should be satisfied, whatever 9 from l to n may be:

$$\frac{L'_9}{L''_9} = \frac{C'_9}{C''_9} = \mu^s.$$

45 The two double ranges are disposed in parallel between the terminals B_1 and B_2 . To these terminals is applied any source capable of developing between the terminals themselves the voltage which actuates the arrangement; the action of the source should be symmetrical, in such manner that the voltage at one of the terminals (with regard to ground) will be at all times equal and opposite to the voltage at the other terminal. For 50 example, as in the schematic diagram (see Fig. 3), there may be connected to the said terminals the secondary T_2 of a transformer, the primary T_1 of which is controlled in the ordinary suitable manner. The middle of the secondary should be 55 at ground, or, in any case, at an invariable voltage.

The transforming voltage that the source develops between the terminals B_1 and B_2 may be, for example, the voltage already defined above.

$$60 e = \Sigma e_n \sin (2\pi f_n t - \phi_n)$$

If the values of all the elements in operation are suitable, there are developed at the output terminals B' and B'' , respectively, the voltages (K being a constant)

$$70 K \Sigma e_n \sin (2\pi f_n t - B_n) \text{ and } K \Sigma e_n \sin (2\pi f_n t - B_n + \alpha)$$

where the phase difference α , the same for all the terms, has the value $\alpha = s\pi$.

75 From this example, which brings to light the essential property of the double ranges of simple

circuits, one may easily deduce the manner of realizing the arrangement in all concrete cases, according to the results to be attained.

In particular, the arrangement applicable to a radiation circuit should, as has been seen, transform the voltage e into the two voltages e' and e'' already defined, for all the terms the phase difference of which has the value

$$\frac{\pi}{2}$$

10

It is evident that this arrangement may be the same as has just been described and the diagram of which is represented in Fig. 3; it is sufficient, naturally, to give to s the value $s = 1/2$.

15

For this value of s the impedance presented by the two double ranges in parallel is quite independent of the frequency; consequently, the internal resistance of the source may be, from this point of view, of any value.

20

It is evident, as shown in Fig. 4, that the transformer T_1 T_2 may be replaced by two identical thermionic tubes 11, 12 symmetrically controlled (push-pull), the anode of one of the tubes being connected to the terminal B_1 and the anode of the other to the terminal B_2 . A resistance of suitable value may be disposed between B_1 and B_2 (and be thus in parallel with the two double ranges), the continuous anode voltage of the two tubes being applied to the middle of this resistance. The output terminals B' , B'' are connected to balanced modulators 13, 14 which suppress the carrier and apply the currents of side band frequency to the antennas A_1 A_3 and A_2 A_4 , respectively. The carrier is applied uniformly to the four antennas but in quadrature phase with respect to the sideband currents.

30

The most suitable values for the different elements of the arrangement may be found with the aid of general theories of radio-electricity. The 40 following figures are given by way of example and are not to be taken as absolute.

The value to take for

$$45 \sqrt{\frac{L'_9}{C'_9}} = \sqrt{\frac{L''_9}{C''_9}}$$

depends upon the characteristics of the source and upon evident considerations; this value will be, in general, of the order of a thousand or several thousand ohms.

50

For μ it may be said $\mu = 4$.

The number N of the simple circuits of each of the two double ranges should depend upon μ , upon the amplitude of the frequency band, and the precision that is desired in the result; the band of frequencies being determined, for example, by $f_m = 30$ cycles per second $f_M = 12000$ cycles per second for a desired degree of precision, one could make $N = 14$.

55

The values of

$$\sqrt{\frac{L'_9}{C'_9}}$$

60 and N being fixed, there will be known, after what has been said above, the order of magnitude of all the inductors and capacitors; in order to learn the exact values it is sufficient to fix the value of a single inductor or capacitor, for example, the value of L'_1 , which is the largest inductance, one could make

$$70 L'_1 = \frac{\mu^{4.5}}{f_m} \sqrt{\frac{L'_9}{C'_9}} = 2.72 \sqrt{\frac{L'_9}{C'_9}} \text{ henrys}$$

The value of resistance R (which represents the total ohmic resistance of the circuit, comprising

75

here that of the inductance coil) and the value of r' depend upon

$$\sqrt{\frac{L'_9}{C'_9}}$$

5 and upon μ ; it is suitable to make

$$R = \frac{1}{0.425} \sqrt{\frac{L'_9}{C'_9}} \text{ ohms}; r' = 0.127R \text{ ohms}$$

10 The capacitors of the simple circuit which occupy the first place in each of the four ranges; that is to say, the capacitors C'_1, C''_1, C'_2, C''_2 , should be extremely large, and therefore difficult to realize. From the practical point of view, it 15 is important to observe that an increase in the value, as large as is wished, of the above capacitors from their theoretical values, has only a negligible influence on the precision of the results given by the arrangement; consequently, the said 20 capacitors may be eliminated (and also, eventually, the capacitor C'_3 , and even C''_3) in reducing the corresponding circuits to only the inductors in series with the resistors.

It is apparent that, among other possibilities, 25 the arrangement may be realized in a manner to give, for each sinusoidal term of the control voltage, a polyphased symmetrical system of voltages having any number of phases. For example, in order to obtain a triphased system, it is necessary 30 to dispose, in parallel between the terminals B_1 and B_2 , three double ranges constituted in the fashion already indicated, and the values of μ, N, R, r' being the same for the three double ranges. The second fundamental relation may 35 be generalized in an apparent manner; by calling, respectively, L'_9, L''_9, L'''_9 the inductors and C'_9, C''_9, C'''_9 the capacitors of the circuit 9 in each of the three double ranges. It is necessary to have, whatever 9 may be.

$$40 \quad \frac{L'_9}{L''_9} = \frac{L''_9}{L'''_9} = \frac{C'_9}{C''_9} = \frac{C''_9}{C'''_9} = \mu^{\frac{1}{2}}$$

The arrangement may undergo several modifications, each to perceive, either in the manner 45 of feeding through a source the essential part of the arrangement, or in the constitution and disposition of the elementary impedances and the ranges of impedances; in particular, in the order in which the constituent elements of each simple 50 circuit are disposed.

55 The phasing network of the present application may be used in conjunction with a system for radiating modulated waves or in any system in which single phase currents are converted into two-phase currents having a similar phase shift over a wide band of frequencies. While the present application claims the phasing network, a co-pending application Serial No. 278,242, filed June 9, 1939, entitled "System of radiation of modulated radio-electric waves," claims the system as 60 a whole.

I claim as my invention:

65 1. A phasing circuit including the combination of a plurality of simple circuits, at least some of said simple circuits including serially connected capacitors and inductors, said simple circuits being connected in four series-parallel rows, where L'_1, L'_2, L''_1, L''_2 represent said inductors and C'_1, C'_2, C''_1, C''_2 represent said capacitors having the relation

$$70 \quad \frac{L'_1}{L'_2} = \frac{C'_1}{C'_2} = \mu$$

where μ is a constant and L'_1, C'_1 and L'_2, C'_2 represent serially connected rows, and the relation

$$\frac{L''_1}{L''_2} = \frac{C''_1}{C''_2} = \mu$$

5

in which L''_1, C''_1 and L''_2, C''_2 represent respectively the other serially connected rows, and in which

$$10 \quad \frac{L'_1}{L''_1} = \frac{C'_1}{C''_1} = \mu^s$$

10

where s is a constant less than unity and input and output connections to said rows, whereby single phase currents applied to the input are derived as two phase output currents having quadrature relation over a band of frequencies.

15

2. A phasing network for deriving two phase currents of substantially quadrature phase from single phase currents covering a range of frequency including four rows of a plurality of parallel simple circuits each responsive to a different resonant frequency, means for connecting two of said rows in series and said two series rows in parallel, said simple circuits being arranged so 25 that the responsive resonant frequencies form geometric progressions in each row, and input connections to said parallel rows and output connections between said series rows and a point of invariable potential with respect to said input 30 connections.

30

3. A network of the character of claim 2 in which each of said simple circuits includes a resistor.

35

4. In a network of the character of claim 2 a push-pull thermionic amplifier having its anode circuits connected to said input connections.

40

5. A phasing network including a plurality of simple circuits each resonant to a different frequency, said simple circuits being connected in parallel and arranged in four series-parallel rows and arranged so that the resonant frequencies form geometric progressions in each row, means for impressing single phase currents of a band of frequencies on said network so that two of said 45 rows present resistive characteristics and two of said rows present respectively reactive characteristics of opposite sign.

45

6. A network of the character of claim 5 further characterized by having a resonant frequency range greater than the range of the applied frequencies whereby throughout the applied range two phase currents of substantially quadrature phase relationship may be derived.

50

7. A phasing network including a plurality of 55 circuits, each of said circuits including resistive and reactive elements, said circuits being connected in parallel, means for connecting in series-parallel four groups of such plurality of circuits, said groups covering different and overlapping 60 bands of frequencies and further arranged to form geometric progressions as to the resonant frequency of the circuits in each group.

60

8. In a network of the character of claim 7, means for applying currents of single phase and variable frequency to said network, and means 65 for deriving from said network two currents of substantially quadrature phase irrespective of the frequency of said applied currents.
